JOSEPH S. WILCOX, JR., OF WORCESTER, MASSACHUSETTS, ASSIGNOR TO NORTON GRINDING COMPANY, OF WORCESTER, MASSACHUSETTS, A CORPORATION OF MASSACHUSETTS.

WHEEL-FEED FOR GRINDING-MACHINES.

1,261,083.

Specification of Letters Patent.

Patented Apr. 2, 1918.

Application filed October 24, 1916. Serial No. 127,398.

To all whom it may concern:

Be it known that I, JOSEPH S. WILCOX, Jr., a citizen of the United States, residing at Worcester, in the county of Worcester and State of Massachusetts, have invented 5 a new and useful Wheel-Feed for Grinding Machines, of which the following is a specification.

This invention relates to a grinding machine, and particularly to improved devices for actuating a wheel feed under all conditions of operation.

It is customary to provide cylindrical grinding machines with a cross feed for the 15 wheel, actuated through a feed lever by dogs adjustably secured to the work table. The wheel is fed toward the work as the table is reversed at each end of its path of travel. This feed mechanism is therefore 20 available only when the table is reciprocated during the grinding operation.

If the wheel is to be fed forward into a groove or recess in the work, or if for any 25 reason the table is not moved longitudinally during the grinding operation, this feed mechanism cannot be used.

It is the principal object of my invention to provide means for actuating the cross 30 feed of the wheel automatically under all conditions of operation.

With this general object in view, one feature of my invention relates to the provision of means for operating the wheel feed from a continuously driven member when 35 the table is not reciprocated, and to the provision of a controlling device by which the feed can be readily changed from intermittent to continuous operation.

A further feature of my invention relates 40 to the provision of devices which insure correct relation of the parts of the intermittent feed mechanism before operative engagement thereof is permitted.

I have also provided an improved device 45 for throwing the feed pawl out of operation when the wheel is to be fed by hand.

Further features of my invention relate 50 to certain arrangements and combinations of parts which will be hereinafter described and more particularly pointed out in the appended claims.

The preferred form of my invention is shown in the drawings in which—

Figure 1 is a front elevation of my improved feed mechanism;

Fig. 2 is a horizontal sectional view taken along the line 2—2 in Fig. 1;

Fig. 3 is an enlarged detail elevation of the throw-off mechanism;

Fig. 4 is a horizontal sectional view of the 60 mechanism for changing the feed, taken along the line 4—4 in Fig. 1;

Fig. 5 is an enlarged detail view of a portion of the mechanism shown in Fig. 4;

Figs. 6 and 7 are end elevations of the 65 sliding clutch member looking in the direction of the arrows 6 and 7 in Fig. 5;

Fig. 8 is a vertical sectional view taken along the line 8—8 in Figs. 1 and 4;

Fig. 9 is a front elevation of the sliding 70 circular rack which transmits motion for the intermittent feed;

Fig. 10 is a detail sectional view taken along the line 10—10 in Fig. 4, and

Fig. 11 is a plan view of the sliding clutch 75 member.

Referring to Figs. 1 and 2, I have shown a ratchet feed wheel 20 rotatable on a shaft 21, (Fig. 2) fixed in the frame 26 of the machine, the wheel being adapted to be 80 clamped to said shaft by a binding nut 22 when so desired. The wheel 20 is provided with a rearwardly extending hub 20^a having teeth cut therein to form a pinion 23, meshing with a gear 24 mounted on a shaft 85 25 which is suitably connected to actuate the cross feed of the grinding wheel.

A feed pawl 27 is pivotally mounted at 28 upon an arm 29 which is supported to turn about the axis of the wheel 20. The 90 feed pawl 27 is provided with a depending arm 27^a which is connected by a link 30 to an actuating mechanism, which will be hereinafter described.

A throw-off plate 31 is pivoted at 32 to 95 the arm 29, and is movable from the full line position shown in Fig. 3 to the dotted line position therein, in which latter position it engages the feed pawl 27 and holds it away from the ratchet wheel 20. A spring 100 33 is connected at one end to a stud 34 on the plate 31 and at the other end to a thin

metal arm 35 which may be adjustably secured to the arm 29 by a nut 36 (see Fig. 2). The pin 34 is so positioned that the spring 33 will yieldingly hold the plate 31 in either 5 of the two positions shown in Fig. 3.

For the manual operation of the cross feed, a handle 40 (Fig. 2) is mounted in an arm 41 which may be clamped to the shaft 21 and ratchet wheel 20 by the binding nut

10 22. At the other end of the arm 41 mechanism M is provided for fine adjustment of the wheel, and a shield 43 forms an automatic stop for the feed. On the opposite side of the arm 41 there is formed a shoulder 44 which engages a lug 45 on the throw-off plate 31 and moves the plate automatically to the dotted line position in Fig. 3 whenever the arm 41 is rotated in a clockwise direction.

15 20 The arm 27^a of the feed pawl 27 is provided with a surface 27^b adapted to engage a surface 31^a upon the throw-off plate 31 when the plate is in the position shown in Fig. 1. When the link 30 moves upward 25 for the idle stroke of the feed pawl, the pawl swings about its pivot 28 on the arm 29 until the surfaces 27^b and 31^a come into contact, after which the arm 29 is swung about its center and the pawl is moved backward 30 while out of contact with the ratchet wheel 20. When the throw-off plate 31 is moved to its dotted line position, the surfaces 27^b and 31^a no longer engage each other.

35 I will now describe the devices for actuating the pawl 27. The link 30 is pivoted at its lower end on a crank pin 50 (Fig. 8) adjustably secured in a slot 51 formed in the face of the crank disk 52. The disk 52 is secured to a shaft 53 rotatable in the frame 40 26 and having a sliding clutch member 54 keyed thereon. A pinion 55 (Figs. 8 and 9) is loosely mounted upon the shaft 53 and engages a circular rack 56 loose upon a rod 57. The rack is positioned upon the rod 45 57 by springs 58 interposed between the rack and the ends of a yoke 59 also slidably upon the rod 57.

50 50 The yoke 59 is provided with a projecting member 60 (Fig. 4) which engages a clutch 61 slidable between oppositely rotated bevel gears 62 and 63, the gear 63 being driven from the gear 62 through a third bevel gear 64. Latches 65 and 66 are provided for holding the clutch member 61 in engagement 55 with one or the other of the driving gears until the latch is released by a feed lever to be described. In Fig. 10 I have shown a detail of one of the ball bearings which permit the yoke member 59 to be moved easily 60 along the rod 57 when the latches 65 or 66 are released.

55 The feed lever is formed in two parts and comprises a depending member 70 (Figs. 1 and 8), having a segment gear 70^a formed 65 on its lower end, fixed to a short shaft 71

rotatable in the frame member 26, and an upwardly extending member 72 also fast to said shaft 71 and having a block 73 mounted therein. The block 73 is adjustable into the path of a dog 74 which may be clamped in 70 any desired position along the side of the table 75. It will be understood that two of these dogs are used, and that they are adapted to engage the block on opposite sides thereof at opposite ends of the path of 75 travel. Such oscillation of the feed lever is effective, through the segment gear 70^a and the sliding circular rack 56, to correspondingly oscillate the pinion 55. When the clutch member 54 is positioned to connect 80 the pinion 55 to the shaft 53, the crank disk 52 and pin 50 will be correspondingly oscillated and will actuate the feed pawl 27. The ends of the segment gear 70^a also alternately engage and release the latches 65 85 and 66.

90 The right-hand face of the clutch member 54 as viewed in Fig. 8 is formed of two unequally spaced projecting portions 54^a (Fig. 7) adapted to engage cooperating projections similarly spaced on the end of the pinion 55. It will be evident that these parts can only engage in a single relative angular position and therefore the crank pin 50 will always assume the same position 95 relative to the segment gear 70^a when the clutch is in mesh.

At the rear end of the shaft 53 (Figs. 4 and 8) a bevel pinion 80 is loosely mounted and engages a bevel gear 81 secured to the 100 continuously rotated bevel gear 63 previously described. The bevel pinion 80 is provided with projecting portions 80^a (Fig. 4) adapted to engage corresponding projecting portions 54^b (Fig. 11) upon the rear face of 105 the sliding clutch member 54. The clutch member 54 is grooved to receive a yoke arm 83 (Fig. 5) carried by a sleeve 84 slidable on a rotatably mounted shaft 85. The sleeve 84 is provided with a spiral groove 86 within which is positioned a pin 87 fixed in the shaft 85. As the shaft is moved angularly the non-rotatable sleeve 84 is necessarily moved axially of the shaft and is effective 110 to move the clutch member 54 into engagement with the pinion 55 or the bevel pinion 80. 115

The shaft 85 is yieldingly positioned longitudinally by springs 88 and 89 which yield to permit the teeth on the clutch to ride over 120 the corresponding teeth on the pinion until they arrive at a suitable position for engagement. The shaft 85 is supported at its outer end in the hub 90 of a handle 91 through which the clutch member is controlled. The 125 shaft is slotted, as at 93, to receive a cross pin 94 in the inner end of the hub 90, the slot permitting the axial movement of the shaft above described. The handle 91 is provided with a spring-pressed plunger 92 130

for holding the handle and clutch in adjusted position.

The operation of my improved mechanism has been largely indicated in connection with the description of the separate parts. When the wheel feed is to be actuated from a reciprocating table the clutch member 54 is moved by the handle 92 into engagement with the pinion 55. As the table is reciprocated the dogs 74 move the feed lever to the right or left, causing corresponding movement of the arm 70 which movement is communicated through the segment gear 70^a, the circular rack 56, the pinion 55, and the shaft 53 to the disk 52 and the crank pin 50, which receive thereby an oscillating movement by which the feed pawl 27 is intermittently actuated as the table approaches each end of its path of travel.

If it is desired to use the wheel feed while the table is held in fixed position, the clutch member 54 is moved into engagement with the bevel pinion 80 continuously driven by the bevel gear 81. Continuous rotation is thus imparted to the crank disk 52 and crank pin 50, and a continuously operated feed of the grinding wheel is thus obtained.

Having thus described one form of my invention it will be evident that changes and modifications can be made therein by those skilled in the art without departing from the spirit and scope of my invention as set forth in the claims and I do not wish to be otherwise limited to the details herein disclosed, but what I claim is:

1. An automatic wheel feed for grinding machines comprising intermittently actuated means for feeding said wheel, mechanically, separately, continuously actuated means for feeding said wheel mechanically, and manual means for changing the system of feed.
2. An automatic wheel feed for grinding machines comprising feed-actuating devices independently operated from a reciprocating member, additional feed-actuating devices operated from a continuously rotated member, and manual means to render either set of devices operative.
3. An automatic wheel feed for grinding

machines comprising a ratchet and feed- 50 pawl, a pawl-actuating shaft, intermittently operated means to oscillate said shaft, separate means to rotate said shaft continuously, and means to connect either of said actuating means to said shaft.

4. A wheel feed for grinding machines comprising a ratchet and feed-pawl, a crank pin, a link connecting said pawl and said crank pin, means to rotatably support said pin, means to adjust the throw of said pin 60 on its support, means to oscillate said pin, additional means to rotate said pin continuously, and a clutch member effective to throw either of said two latter means into operation.

5. A wheel feed for grinding machines comprising a ratchet and feed-pawl, a crank pin, a link connecting said pawl and said crank pin, a disk to which said pin is adjustably secured, a shaft for said disk, an 70 oscillating member and a continuously rotated member each loose on said shaft, a clutch member keyed to said shaft and effective to secure either the oscillating or the rotating member to the shaft, and means to 75 move said clutch member.

6. A wheel feed for grinding machines comprising a shaft, an oscillating member and a continuously rotated member each loose on said shaft, a clutch member effective to secure either the oscillating or the rotating member to the shaft, and means to move said clutch, provision being made to insure engagement of said clutch member and said oscillating member in a single pre- 85 determined angular relation.

7. A wheel feed for grinding machines comprising a shaft, an oscillating member and a continuously rotated member each loose on said shaft, a clutch member effective to secure either the oscillating or the rotating member to the shaft, and means to move said clutch, including devices adapted to yield if the members are not in position for immediate engagement.

In testimony whereof I have hereunto affixed my signature.

JOSEPH S. WILCOX, Jr.

It is hereby certified that in Letters Patent No. 1,261,083, granted April 2, 1918, upon the application of Joseph S. Wilcox, Jr., of Worcester, Massachusetts, for an improvement in "Wheel-Feeds for Grinding-Machines," an error appears in the printed specification requiring correction as follows: Page 3, line 3, claim 1, after the word "wheel" strike out the comma; and that the said Letters Patent should be read with this correction therein that the same may conform to the record of the case in the Patent Office.

Signed and sealed this 23d day of April, A. D., 1918.

[SEAL.]

F. W. H. CLAY,

Acting Commissioner of Patents.

Cl. 51—4.
